Patented June 27, 1922.

UNITED STATES PATENT OFFICE.

STEPHEN BATTNER, OF BROOKLYN, NEW YORK.

PNEUMATIC-ACTION UNIT.

1,420,678.

Specification of Letters Patent. Patented June 27, 1922.

Application filed August 25, 1920. Serial No. 405,804.

To all whom it may concern:

Be it known that I, STEPHEN BATTNER, a citizen of the United States, and a resident of Brooklyn, in the county of Kings and State of New York, have invented certain new and useful Improvements in Pneumatic-Action Units, of which the following is a specification.

This invention relates to pneumatic actions for automatic and other musical instruments such as organs, pianos, or the like, and has particular reference to the construction of pneumatic action value units for such instruments.

Among the objects of the invention are the following: To simplify the mechanism, with reference to economy of construction, facility of assemblage, and control; to provide a pair of units, rights and lefts, with a single vacuum chamber between them and common to the valves of both units; to provide that all the diaphragms of all the valves shall be in the same row and the valves shall all be in a single row, the two rows being arranged so that the valves are preferably below the diaphragms; to generally improve this class of devices with respect to reliability of action and uniformity of construction; to provide each valve unit so that the entire body thereof is a single block or piece of material, and to provide an action unit in which the body is of the thinnest possible construction, occupying a minimum amount of space lengthwise of the series, and in each of which a diaphragm and its correlated valve lie in approximately the same plane.

With the foregoing and other objects in view the invention consists in the arrangement and combination of parts hereinafter described and claimed, and while the invention is not restricted to the exact details of construction disclosed or suggested herein still for the purpose of illustrating a practical embodiment thereof reference is had to the accompanying drawings, in which like reference characters designate the same parts in the several views, and in which:

Figure 1 is a detail perspective showing a pair of unit blocks spaced laterally from normal position;

Figure 2 is a vertical view of a plurality

of units, complete, one unit being in elevation and another being in section on the line 2—2 of Figure 3, and

55

Figure 3 is a vertical transverse section of the complete combination.

Referring now more specifically to the drawings I show my improvement as comprising a series of action units all in the same row and arranged in pairs, the units of each pair being rights and lefts and indicated at A and B respectively. Each unit consists of a single integral body of generally rectangular form, of any suitable material, such as wood or sheet material such as metal, and each formed with its upper portion hollow as by boring, establishing a vacuum chamber 10, open on the side adjacent to the other block of the same pair. 60 Each chamber 10 is counterbored at 10^a over which is fixed a diaphragm 11, free at its center to act under the influence of a puff of air admitted beneath it, as through a port 12 leading thereto from a tracker board, as 65 well understood.

From the chamber 10 is formed a downward extension 13, and in the center of the lower end of this extension is formed a hole 14 the wall of which constitutes a seat for 80 a valve 15, normally seated against the side thereof opposite the extension 13. The body is counterbored at 16 to accommodate the valve, and the valve chamber so formed is closed on the outside by a plate or cap 17 85 having a port opening 18 from the atmosphere.

The valve support is shown as a lever 19 of the first class, pivoted at 20 on an axis supported horizontally in bearings 21 located in the chamber extension 13, the lower longer end of the lever being bent at an angle and attached to the valve, while the shorter upper end of the lever bears against the diaphragm or a button 22 fixed thereto. 90 From Figure 2 it will be appreciated how thin the unit is and how the diaphragm and valve lie approximately in the same vertical plane and well within the unit block, as distinguished from parallel planes or otherwise 95 as heretofore, occupying much greater space. It will be noted too that the two opposing diaphragms of each pair constitute the walls 100 of the same vacuum chamber and that there

is really but one chamber or vacuum space for each two blocks.

23 indicates a frame or bar to which the unit blocks are or may be attached in any approved manner. To this frame is connected a vacuum chest 24 common to all of the vacuum chambers through vacuum ports 25 with which register lateral ports 26 from the vacuum chambers 10. The frame 23 is 10 also bored at 12^a to register with the ports 12.

For each valve chamber 16 is a lateral port 27 communicating with a port 28 leading through the frame 23 to any suitably arranged pneumatic 29. These pneumatics 15 may be arranged in any convenient manner, depending upon the size thereof. In this connection I wish to point out that the novel construction of my units adapts them to be made of a single uniform size and 20 character for all sizes of instruments and then for the larger instruments whose actions are correspondingly large, or should be for the best results, the pneumatics may be made as large or wide as desired by arranging them one above another.

Normally the valve 15 is held seated against the seat, closing the port 14 as shown in Figure 2, by the vacuum within the chamber 10, the diaphragm 11 being collapsed through any suitably disposed bleed port 30 leading as shown to a bleed chamber 31 common to all the valve units, for the convenience of construction and adjustment. Thus equilibrium of pressures obtains on 35 both sides of the diaphragm. When a puff of air is admitted beneath the diaphragm through the ports 12^a and 12 the short upper end of the lever is thrown outward and this movement being multiplied through the 40 longer lower end throws the valve in the other direction opening the port 14 and closing the port 18. The normal atmosphere in the pneumatic pertaining to this valve is then dissipated through the ports 28 and 27, 45 chamber 16, and port 14 to the vacuum chamber 10 and chest 24. The moment the admission of air ceases at the tracker board the diaphragm and valve return to normal position and the pneumatic is again filled

with air admitted thereto through the ports 50 18, 27, and 28.

I claim:

1. A series of valve units arranged in pairs, the units of each pair being formed with a vacuum chamber common to both units, 55 and a pair of diaphragms in said chamber and having their axes coincident with each other at right angles to said chamber.

2. A series of valve units each having a diaphragm, there being formed a vacuum 60 chamber between each two units, the diaphragms thereof being directly opposite each other and constituting the side walls of the chamber.

3. A series of valve units comprising pairs 65 of unit blocks arranged as rights and lefts, the blocks of each pair having a vacuum chamber between them common to both, the chamber having an extension, each block having a valve chamber opposite the end of 70 the extension, and means lying within said extension serving to support and actuate the valves.

4. A series of pneumatic units, each comprising a diaphragm and a valve, the diaphragms of all units of the series being in 75 the same row and lying in substantially parallel planes and all the valves being in the same row and having a common axis, the valves being in a different row from the dia- 80 phragms.

5. A pair of pneumatic valve units comprising two mating blocks arranged face to face, each block having a valve chamber and another chamber constituting one-half of a 85 vacuum chamber, a valve located in each valve chamber, a diaphragm in the bottom of each half vacuum chamber, the diaphragms of the pair of units constituting the walls of the vacuum chamber, and independent valve actuating means leading from the diaphragms to the respective valves along the same vacuum space.

Signed at New York in the county of Bronx and State of New York this 20th day 95 of August, A. D. 1920.

STEPHEN BATTNER.
